LEG SUPPORT DEVICE

Filed Sept. 13, 1947

UNITED STATES PATENT OFFICE

2,473,947

LEG SUPPORT DEVICE

Walter P. Hamstrom, Seattle, Wash.

Application September 13, 1947, Serial No. 773,913

3 Claims. (Cl. 155—165)

1

My present invention relates to the general field of automobile accessories and more particularly to a leg support device.

In driving an automobile, particularly for long periods, considerable fatigue, both physical and nervous, is experienced in the right foot and leg, due to the fact that this leg must actuate the foot throttle of the car. In hilly country, the throttle must be accurately positioned to properly control the speed of the car and the output of the motor, and this imposes tension on the right leg of the operator extending over long periods. My present invention has, as its primary purpose, the provision of means of relieving the automobile driver of this unnecessary strain and fatigue.

The principal object of my present invention, therefore, is to provide a leg rest for the foot-throttle-operating leg of the car driver, which is so arranged so as to reduce fatigue and strain to a minimum.

A further object of my present invention is to provide a leg rest for use in an automobile which is readily adjustable for height, so that just sufficient support is given the operator's leg to relieve strain and fatigue without in any way impairing the circulatory system.

A further object of my present invention is to provide a leg rest unit that is capable of being swung from one position to another transversely of the car, so that the angle of the operator's leg can be quickly and easily changed.

A further object of my present invention is to provide a leg rest so arranged that the leg supporting member can be twisted or turned about the vertical axis of the support, so that the supporting pad can be accurately positioned for maximum comfort of the operator.

A further object of my present invention is to provide resilient means within my leg-supporting device so that minor road shocks will not be transmitted from the car to the driver's leg.

A further object of my present invention is to provide a height adjustment that is capable of infinitely close settings, and which will yield if undue road shocks are encountered.

Further objects, advantages and capabilities will be apparent from the description and disclosure in the drawings, or may be comprehended or are inherent in the device.

In the drawings:

Fig. 1 is a perspective view showing the manner in which my leg support device is used.

Fig. 2 is a perspective view showing the details of structure of my leg support.

2

Figs. 3, 4, and 5 are fragmentary vertical sectional views taken along similarly numbered cutting planes of Fig. 2.

Referring more particularly to the disclosure in the drawings, the numeral 10 designates the leg rest pad of my device. This I prefer to form with a curved transverse section so as to generally support the leg of the user well across that section of the leg. It should also have reasonable length so that the bearing pressure on the leg can be kept at such a low degree as to in no way interfere with the blood circulatory system. Normally, I prefer to form this member of sheet stock, either of the lighter weight metals or the plastic materials. Secured to the bottom center of pad 10 is a positioning sleeve 12. This sleeve should be fixedly secured to pad 10 and have sufficient downward extension so as to provide adequate bearing against the possibility of the pad rocking. When used on a vertical member 14 of reasonable size, the overall length of sleeve 12 should be sufficient so that a buffer spring 16 may be employed, after the showing of Fig. 3, so that the small shock incidental to normal driving will be taken care of at this point and not transmitted from the body of the car to the user.

It must be borne in mind while considering this feature of the design that the driver of a car has his weight supported largely by the spring system of the seat cushions. Consequently, as the car moves considerably in the vertical plane, he may tend to stay more or less in a given horizontal plane. On the other hand, his foot, resting on the floor of the car, naturally moves with the car body, and this supporting device which I have provided, being positioned intermediate these two extremes, must of necessity take care of certain displacements if it is going to serve its proper purpose. In other words, it could not be a fixed member, or unnecessary shock would be transmitted to the driver's leg. Therefore, it follows that the overall length of spring 16, or whatever other cushioning device may be employed, must be adequate to take care of the minor deflection so caused.

To secure pad 10 to its supporting shaft 14, I provide a pin 18 which is fixedly secured at the upper end of tube 14 and is adapted to reciprocate within a slot or guide 20 formed in sleeve 12. This pin also provides a convenient abutment for spring 16. These constructions are probably best illustrated in Figs. 2 and 3.

Shaft 14, which may be either a solid or tubular member, is adapted for telescoping within the

main support or pivot tube 22. This tube in turn is pivotably supported to the bracket or shoe 24, as by pin 26.

I have illustrated shoe 24 as having the flange members 28, which are arranged so that the shoe can be riveted or otherwise secured to the floor of the automobile. I then provide as part of shoe 24 a U-shaped wall 30, which has sufficient upward extent to form a guide for my supporting members 14 and 22, so that there will be no longitudinal movement of pad 10 when my device is installed under conditions of use.

It is, however, desirable to have transverse movement of the device and to provide limits for that transverse movement. I therefore have arranged that the curved portion 32 of wall 30 will form one end limit and then I provide holes that pass in pairs through both walls of member 30 as 34, 36, and 38. Through these holes, the operator of the car can insert a suitable pin after he has determined the maximum of transverse movement to be desired. It has been found that the most convenient pin for this use is a split pin made after the fashion of a cotter, in that, of its own resiliency, it provides a locking security for the pin, yet permits its easy removal for subsequent change as adjustments become desirable.

It next becomes desirable that a friction securing means be provided to hold the vertical shaft 14 in adjusted position with respect to shaft 22. There are two actions which can only be fulfilled by some form of friction engagement. One is the desirable feature that the angular position of rest portion 10 should be capable of easy adjustment with respect to the longitudinal axis, for instance, of foot 24, so that as an operator changes his leg position, pad 10 should follow that change without undue attention from the operator, and I have provided the device shown in Figs. 2 and 4 to achieve this form of operation. A second requirement is that when a very severe jolt is encountered by the car, instead of it being transmitted to the leg of the driver, the frictional engagement between members 14 and 22 should act as a safety release and permit any rapid movement to cause a slippage of these two members rather than transmit the full force of the impact to the driver. To achieve these purposes, I have provided a friction locking means which consists of a locking collar 40 having a bore 42 of a size so that normally shaft 14 can slide freely through it, but when the collar 40 is tipped or canted, the square edges of opening 42 will bite into, or at least provide extreme frictional pressure on the shaft 14 and arrest its movement.

The canting of washer 40 is achieved by having the upper end of the hollow shaft 22, as 44, beveled at the approximate angle shown in Fig. 5 and that means be provided, as spring 46, to insure a definite tendency for the washer to seek to engage surface 44. This provides a trouble-free release means which under normal pressure conditions prevents slipping of the two members. Spring 46, however, should be so selected and adjusted that undue shock will cause a slippage at this point.

In order to permit free movement of shaft 14, I provide the finger lever portion 48 which, when it is pressed in towards the tube, causes washer 40 to assume a position normal to the shaft 14 and permit its free passage therethrough. It is to be noted that I have employed ears struck from member 40 and tube 22 to provide the locating means for washer 40 and the spring positioning

means for spring 46. This has been found to be convenient and economical.

It is believed that it will be clearly apparent from the above description and the disclosure in the drawings that the invention comprehends a novel construction of a leg support device.

Having thus disclosed the invention, I claim:

1. A leg-supporting device for use by automobile drivers, consisting of: a transversely curved leg rest pad; a telescopic support for said pad having a pivoted tube and a supporting shaft slidable within said pivoted tube; buffer means disposed between said leg rest pad and said supporting shaft; friction locking means adapted to secure said telescopic support in adjustable height position; a bracket adapted to be secured to the floor of an automobile and to pivotably support said telescopic support; said bracket having a U-shaped wall adapted to guide said telescopic support and restrict it to movement in one plane; a plurality of aligned holes through said U-shaped wall disposed to receive limit stop pins adapted to limit the extent of movement of said telescopic support.

2. A leg-supporting device for use by automobile drivers, consisting of: a transversely curved leg rest pad; a telescopic support for said pad having a pivoted tube and a supporting shaft slidable within said pivoted tube; compression means disposed between said leg rest pad and said means adapted to limit the displacement between said pad and said supporting shaft; friction locking means adapted to secure said telescopic support in adjustable height position; a bracket adapted to be secured to the floor of an automobile and to pivotably support said telescopic support; said bracket having a U-shaped wall adapted to guide said telescopic support and restrict it to movement in one plane; a plurality of aligned holes through said U-shaped wall adapted to receive limit stop pins adapted to limit the extent of movement of said telescopic support.

3. A leg-resting device for use by automobile drivers, consisting of: a transversely curved leg rest pad; a telescopic support for said pad having a pivoted tube and a supporting shaft slidable within said pivoted tube; buffer means disposed between said leg rest pad and said supporting shaft; friction locking means adapted to secure said pivoted tube and said supporting shaft in adjustable height position; a bracket adapted to be secured to the floor of an automobile and to pivotably support said telescopic support; said bracket having means adapted to guide said telescopic support and restrict it to movement in one plane; adjustable stop means adapted to limit the extent of movement of said telescopic support.
